[57] **CLAIM**

The ornamental design for adjustable mirror, as shown and described.

DESCRIPTION

FIG. 1 is a front, elevational view of an adjustable mirror with the mirror in a fully raised position showing our new design;

FIG. 2 is a side elevational view, the opposite side being a mirror image thereof;

FIG. 3 is a rear elevational view thereof;

FIG. 4 is a top plan view thereof;

FIG. 5 is a bottom plan view thereof;

FIG. 6 is a side elevational view with the mirror shown in partially lowered position, the broken lines are for environmental purposes only and form no part of the claimed design; and,

FIG. 7 is a perspective view thereof, the broken lines are for environmental purposes only and form no part of the claimed design.
